CLAIM

The ornamental design for a display screen or portion thereof with graphical user interface, as shown and described.

DESCRIPTION

FIG. 1 is a front plan view of a display screen or portion thereof with graphical user interface showing a first embodiment of my new design;

FIG. 2 is a front plan view of a display screen or portion thereof with graphical user interface showing a second embodiment of my new design;

FIG. 3 is a front plan view of a display screen or portion thereof with graphical user interface showing a third embodiment of my new design; and,

FIG. 4 is a front plan view of a display screen or portion thereof with graphical user interface showing a fourth embodiment of my new design.

The outermost broken lines illustrate a display screen, which forms no part of the claimed design. The remaining broken lines illustrate portions of the graphical user interface, and forms no part of the claimed design.

1 Claim, 4 Drawing Sheets
